DISPLAY STAND FOR PHOTOGRAPHS AND THE LIKE

Frederick L. Jahn, Pittsfield, Mass., assignor to Eaton
Paper Corporation, Pittsfield, Mass., a corporation of Delaware

Filed Oct. 23, 1963, Ser. No. 77,104

Term of patent 14 years

(Cl. D80—9)

FIG. 1 is a perspective view of a display stand for photographs and the like, showing my new design, several of the photograph holders being omitted and the remaining holders being broken away for convenience of illustration;

FIG. 2 is a reduced elevational view thereof; and

FIG. 3 is a top plan view thereof.

I claim:

The ornamental design for a display stand for photographs and the like, as shown.
